UNITED STATES PATENT OFFICE.

MARK L. BRILLIANT, OF SAN FRANCISCO, CALIFORNIA, ASSIGNOR OF ONE-HALF TO
CHARLES E. BRINKMAN, OF SAN FRANCISCO, CALIFORNIA.

DAVENPORT-BED.

1,651,011.

Specification of Letters Patent. Patented Aug. 24, 1920.

Application filed August 5, 1918. Serial No. 243,392.

To all whom it may concern:

Be it known that I, MARK L. BRILLIANT, a citizen of the United States, residing at San Francisco, in the county of San Francisco and State of California, have invented new and useful Improvements in Davenport-Beds, of which the following is a specification.

This invention relates to a davenport bed. One of the objects of the present invention is the production of a bed of the character described which is so constructed that when arranged to form a sofa or davenport there will be nothing to indicate that it is convertible into a bed and when unfolded will form a bed wherein a wide mattress is presented and firmly supported for use, while the upholstered seat of the davenport is turned down and located under the front part of the mattress so as to be protected during the use of the device as a bed.

Another object of this invention is to provide a sectional foldable mattress frame which is adapted to carry a mattress support constructed of coil springs, the sectional frame when folded being so arranged that ample space for the mattress and bedding is provided.

Another object of the invention is to provide a bed the foldable sections of which will counterbalance each other during the extending or folding of the bed, thus rendering it comparatively easy for anyone to manipulate the same.

Another object of the invention is to provide a bed of the character described in which the arm sections of the davenport are extended when the mattress frame is unfolded to form a support therefor and also to permit ready access to the bed from either side without any interference from the davenport arms or side sections as is usually the case.

Further objects will hereinafter appear. The invention consists of the parts and the combination and the construction of parts as hereinafter more fully described and claimed, having reference to the accompanying drawings, in which—

Figure 1 is a cross section of the davenport bed showing it in the folded position.

Fig. 2 is a similar view showing the bed extended.

Fig. 3 is a detail view of the foot board.

Fig. 4 is a plan view of the bed partly 55 in section.

Referring to the drawings in detail A indicates in general the main frame of the davenport. This frame consists of a back section 2 and a pair of end sections 3. 60 Hingedly secured as at 4 to the upper edge of the back section is a cover section 5 which is upholstered as at 6 to give the davenport ornamental appearance and also to form a portion of the back rest of the 65 davenport. Formed in the end sections 3 is an offset as shown at 7 and 8 and adapted to be supported on the surface 8 is a pair of arm sections 9. These arm sections are pivotally attached to a pair of link arms 10 70 which are free to swing about a pivotal member 11 from the position shown in Fig. 1 to the position shown in Fig. 2. The arm sections 9 are connected by means of a cross member 12, the front face of which is up- 75 holstered as at 13 to form a continuation of the back rest shown at 6. The forward ends of the arm sections 9 are finished with post-like projections 14 and the inner or rear ends of the back sections are pro- 80 vided with similar posts 15 which coöperate with the front posts to form supporting legs for the forward portion of the bed when it is extended as in Fig. 1. The legs 15 being slightly longer than the legs 14 to 85 form the real supporting legs. The upper surfaces of the arm sections 9 may be up- 90 holstered as shown at 16 or finished in any other suitable manner while the seat portion is also upholstered as at 17, said up- 95 holstered section being supported by coil springs 18. The coil springs here shown are in reality double and are secured or supported in a mattress frame generally indicated at 19. This frame may be constructed 95 of angle iron or like material and consists of two side bars 19 and an end connecting bar 20, all rigidly secured to the seat frame comprising the arms 9 and the cross member 12.

The mattress frame as a whole consists of an inner and outer main section such as shown at 19 and 21 and an intermediate section 22. The inner section of the mattress frame is constructed similar to the outer section to the extent that it consists of a pair of side bars 21 which in this instance are connected by means of a head board 23. This

board is pivotally attached to the inner end of the side bars as at 24 and its opposite end is provided with a pin-like projection upon which are journaled rollers 25. These rollers travel in slotted plates 26 secured in each end section 3 of the main frame, said slotted plates being curved substantially as shown at 27 to form a support for the head board when extended as shown in Fig. 2. The intermediate section of the mattress frame shown at 22 consists of a pair of side rails which are pivotally connected at each end as at 28 and 29 to the inner and outer sections of the mattress frame as shown. The intermediate section assumes an alignment with the other sections of the mattress frame when extended and it assumes a vertical position as shown in Fig. 1 when the mattress frame sections are folded. It will to this extent also form a spacer between said mattress frame sections thereby providing ample space as shown at 30 for the reception of a mattress and bedding. The outer mattress frame 19 is pivotally attached to the arms 10 by means of a pair of angle brackets 31, while the inner mattress frame is supported by means of a pair of links 32. These links are pivotally secured to a bearing plate 33 secured one to each end member 3 of the main frame, said pivotal connections being shown at 34 and 11. The arms 10 are also pivotally attached to this plate as shown at 11 and a connection is made between the forward links 32 and the arms 10 by means of slotted intermediate links 34^a. Each mattress frame section has secured therein a series of coil springs 18 for the support of a mattress, the coil springs being secured between the side and end bars of the frame in any suitable manner. The springs employed in the inner and intermediate sections being single as shown, while the springs in the outer section are double to form a support not only for the mattress but also for the upholstered seat section 17.

In actual operation with the bed folded as in Fig. 1 it can readily be seen that a davenport is formed which in appearance does not give the impression that it is a folding bed. This is due to the fact that all folding parts are absolutely inclosed and that the davenport is upholstered and finished in the usual manner. If it is desired to employ the bed it is only necessary to lift the cover section 5 until it has assumed the dotted line position shown at 5^a. The arm sections 9 are then grasped by the rails and swung outwardly in the direction of arrow *a* between the arms 10. These arms will simultaneously swing outwardly about the pivots 11, and the intermediate connecting links 34^a will then exert a pull on the forward links 32, thus causing the inner frame to rise from the lowered position shown in Fig. 1 to the complete raised position shown in Fig. 2. This position being assumed when the outer section has been fully unfolded. The outer section is here supported by the legs 15 while the intermediate section is supported by the side bars 19 and 21, the side bars 21 being in turn supported by the links 32, while the head board 23 is supported by the curved portion of the slotted plates 26. The head board will first rise vertically when the mattress frame sections are unfolded. It will then lower itself as the folding operation takes place and will finally assume the inclined position shown in Fig. 2 when the sections have been completely extended. All parts of the bed are thus rigidly supported and it can also be seen that practically any length and width mattress may be obtained by merely increasing or decreasing the size of the davenport. It can also be seen that as the arm sections have been extended that the mattress or bed is entirely open and accessible from either side. No obstruction is therefore presented and the general appearance is more that of an ordinary bed than the usual forms of folding sofas and davenports now employed.

After the bed has been extended as shown in Fig. 2 it is possible to release the bedding by extending a foot board such as shown in Figs. 2 and 3 to the dotted line position as shown at 40. This foot board is carried by two slotted arms 41 and also serves the function of a mattress or bed clamp when the bed is to be refolded. That is, the foot board may be swung forward in the direction of arrow *b* about a pair of pins 42 extending through the slotted arms. The foot board is then moved downwardly on the pins until the full line position is assumed as shown in Fig. 3. It will here act as a clamp and is positively locked against movement as the lower edge of the slotted arms engages the cross bar of the mattress frame. The bed may now be refolded if desired by merely lifting upwardly on the frame in the direction of arrow *c*.

For the purpose of entirely hiding the interior mechanism I provide a hinged section 44. This is connected with the arms of the seat section 17 by a finishing cloth 45. The cover section 5 being also provided for the same purpose gives the davenport a finished and artistic appearance when the bed is folded and adds comparatively little to the general cost of the structure.

A bed constructed as here shown is comparatively light and can be cheaply manufactured due to the fact that ordinary strap and angle iron is employed throughout its manufacture. The bed is furthermore easily handled when it is desired to move it from one room to another or to ship it as the mattress frames may be lifted out entirely by

merely removing the bearing plates 26 and 33 upon which the several links are pivotally supported. The bed may therefore be quickly disassembled if desired and may 5 therefore be shipped in a more compact unit or in several parts if desired.

While certain materials and proportions are here specified I wish it understood that these features may be changed or varied as 10 the experience and judgment of the manufacturer may dictate.

Having thus described my invention what I claim and desire to secure by Letters Patent is—

15 1. A davenport comprising a fixed main frame, a seat section on said frame, a pair of swinging arms between which said seat section is pivotally mounted on the main frame, a mattress frame secured on the lower side of said seat, an intermediate frame connected with one end thereof, an inner frame connected to the intermediate frame, means actuated by unfolding of the seat section for raising the intermediate and the inner frame into alignment with the first frame secured to the seat, a head board pivotally connected to the inner end of the inner frame, and means guidingly engaging the outer end of the head board to allow same 20 to slide vertically, said means being formed to engage said outer end of the head board and to support same at an incline upon the mattress frame reaching a horizontal position.

2. A davenport-bed comprising a main frame section, a seat section, a mattress frame secured on the underside of the seat section, a pair of arms pivotally mounted on the main frame, said seat section being pivotally mounted between the free ends of said arms, a pair of links pivotally mounted on each end of the main frame, a mattress frame supported between said links, an intermediate mattress frame connecting said frame and the first named frame, a pair of intermediate links connecting the arms with the first named links to permit swinging movement of the arms when the bed is unfolded to raise said links and the mattress frame section carried thereby, a head board pivotally attached to the inner end of the mattress frame section, a pair of slotted plates secured one at each end of the main frame, rollers on each end of the head board projecting into said slotted plates, and offset

portions on said slotted plates adapted to support the head board in a slightly inclined position when the mattress frame sections are unfolded.

3. A davenport bed comprising a main 60 frame, a pair of arms pivotally mounted on said frame, a seat member supported by the frame and pivotally secured between the arms, a pair of arm sections on the seat member, a back rest on the seat member, a cover 65 member on the main frame; said cover member being hingedly secured thereto and having a back portion thereon forming a continuation with the back section carried by the seat, said cover also forming a lock to 70 prevent movement of the seat with the arms or about the arms, and a sectional mattress frame connected with the seat adapted to be folded or extended as the seat is folded or

75

4. In a davenport bed, a main frame, a seat member, a mattress frame having connected inner, outer and an intermediate section, links pivoted at their upper ends to the inner section and at their lower ends to 80 the main frame, brackets connected to the outer section and depending therefrom, and arms pivoted to the lower ends of said brackets and to the main frame and having a substantially horizontal disposition in unfolded 85 position of the parts, the seat member being connected to the outer section, said arms and brackets each lying vertically and outwardly of and substantially parallel to the intermediate section in folded position of the 90 parts.

5. In a davenport bed, a main frame, a seat member, a foldable mattress frame connected to said main frame and member, a head section pivoted to the mattress frame, 95 vertical guides having offset portions borne by the main frame, and means connected to the outer end of the head section and operating in said guides and engageable with the offset portions thereof when the mattress 100 frame is horizontal to hold the head section at an incline.

In testimony whereof I have hereunto set my hand in the presence of two subscribing witnesses.

MARK L. BRILLIANT.
